UNITED STATES PATENT OFFICE.

HARRY T. LOOMIS, OF NEW YORK, N. Y., ASSIGNOR TO FRANK & LAMBERT, INC., OF NEW YORK, N. Y., A CORPORATION OF NEW YORK.

DESIGN FOR A TEXTILE FABRIC.

43,178.

Specification for Design.

Patented Oct. 22, 1912.

Application filed August 27, 1912. Serial No. 717,408. Term of patent 3½ years.

To all whom it may concern:

Be it known that I, HARRY T. LOOMIS, a citizen of the United States, and residing in the borough of Manhattan, in the city of New York and State of New York, have invented a new, original, and ornamental Design for a Textile Fabric, of which the following is a specification, reference being had to the accompanying drawing, forming part thereof.

The figure is a plan view of a portion of textile fabric showing my new design.

I claim:—

The ornamental design for a textile fabric, as shown.

HARRY T. LOOMIS.
